CLAIM

The ornamental design for a knife stand, as shown and described.

DESCRIPTION

1. Knife stand

1.1 : Front

1.2 : Back

1.3 : Top

1.4 : Bottom

1.5 : Left

1.6 : Right

1.7 : Reference

The broken lines in reproductions 1.1 through 1.6 and at the base of the knife stand in reproduction 1.7 illustrate portions of the knife stand forming no part of the claimed design. The broken line showing of the knives in reproduction 1.7 is for the purpose of illustrating environmental subject matter that forms no part of the claimed design.
